UNITED STATES PATENT OFFICE.

WILLIAM L. DEMING, OF SALEM, OHIO, ASSIGNOR TO THE DEMING COMPANY, OF SALEM, OHIO, A CORPORATION OF OHIO.

GREASE GUN.

Application filed September 4, 1920. Serial No. 408,222.

To all whom it may concern:

Be it known that I, WILLIAM L. DEMING, a citizen of the United States, residing at Salem, in the county of Columbiana and State of Ohio, have invented a certain new and useful Improvement in Grease Guns, of which the following is a full, clear, and exact description, reference being had to the accompanying drawings.

10 This invention relates to grease guns and has for its objects a provision of means for effectively forcing an entire charge of material out of a container; together with a construction of a cooperating head and spout, which will be adapted to draw a charge of material into the container without forming an excessive air pocket therein.

15 The above and other objects will be set forth in the following description which relates to the drawings, and the essential characteristics thereof are set forth in the claims.

20 The drawings show the invention embodied in a device suitable for use as a grease gun; Fig. 1 is an elevation of such grease gun; Fig. 2 is a longitudinal section thru the center thereof; Fig. 3 is a transverse section taken on the lines 3—3 in Fig. 2; Fig. 4 is an enlarged fragmentary section of the plunger head and spout; Fig. 5 is an elevation of the expander ring.

25 Designating the parts by the use of reference characters, 10 represents a cylinder, adapted to hold a charge of grease or heavy oil, one end of which is enclosed by a cap 11, the other end being open thru the spout 12. A reciprocating piston 13 is adapted to move within the container 10 by means of force exerted on the handle 14. This general arrangement is such as is customarily used in devices of this character, and the novel features of my invention are embodied in the construction of the spout 12, together with the cooperating piston head 15.

30 The cylinder 10 is preferably threaded at one end to receive the usual cap 11, and at the other end to receive the spout 12. The cylinder may be constructed of any hollow tubing suitable as a container for grease, the interior portion thereof being preferably smooth to provide for a close fit between the cylinder and the piston which is adapted to reciprocate therein. The cap 11 is preferably so constructed that it may be readily removed to facilitate the removal of the

35 My reciprocating piston, which is adapted to be moved within the cylinder and is secured to the end of the rod 13, comprises a member having a substantially conical shaped tip 20, which merges into a cylindrical portion 21, and which may be secured to the end of the rod by a threaded engagement therewith or by any suitable means. I have shown a piston head having a centrally positioned cylinder 22 with a hollow space 60 between the center and the walls of the head. This space has been provided not only to lessen the weight of the head but also to afford effective supporting surface against the outer portion of the packing cup 25, 65 shown as abutting the end of the cylindrical portion 21 and closely embraced by the walls of the cylinder 10.

70 A packing cup 27, similar to the cup 25 but separated therefrom by the spacing plate 26, is rigidly held against the head by the washer 28 and the expander ring 29. The expander ring comprises a cup-shaped member preferably stamped from a flat disk and having an annular bowed portion 40, together with a plurality of kerfs 41 extending from the bowed portion to the periphery of the disk. The bottom portion 42 being flat serves as a washer to hold the cup 27 against the head, while the periphery serves to force 75 the packing cup against the walls of the cylinder, thereby effecting an air-tight joint and insuring a charge of grease that is free from entrapped air. The outside diameter of the cylindrical portion 21 is preferably such that 80 the thickness of the packing cup 25 may lie between the head and the cylindrical wall. The tip 30 of the head is preferably rounded so as to partially center the head when it reaches the opening in the spout. 85

90 To carry out the object above named of facilitating the forcing of the entire contents from the grease gun, I have constructed the spout of the grease gun in the form of a combined funnel and spout, the funnel portion comprising the end wall of the cylinder 10, whereby the complementary conical plunger may function to force the oil or grease from the cylinder. As shown in the drawings, 32 is this conical or funnel section 95 mentioned merging into the cylinder portion 31, threaded on the cylinder 10 and preferably integral with the spout or tip 33, which is reinforced by a slight enlargement indicated at 35 at the extreme end. The interior 100

105 110

- part of the conical section 32 is substantially complementary to the exterior portion 20 of the head 15, and the apex of the cone is positioned on a line with the axis of the head.
- 5 The tip 33, however, is shown as positioned obliquely to the axis of the head to enable an operator to lubricate bearings that would be inaccessible with the straight tip. The enlarged head 35 at the tip may facilitate the
- 10 attachment of a hose or tube.
- In operation the tip 33 is inserted within a grease container while an operator forces the handle 14 inwardly until the head 15 abuts the spout 12. As the handle is drawn
- 15 outwardly the charge of grease or other material is drawn into the container 10 and practically fills the space therein, the operator then removes the pump from the container whereupon it is ready for use.
- 20 From the foregoing description it will be seen that I have provided a device which is adapted to draw in and hold a charge of grease or heavy oil without entrapping air; that I have provided a mechanism which is
- 25 capable of discharging all of the grease held within the container thereby eliminating the possibility of corners being clogged with grease and thus necessitating cleaning. It will also be apparent that I have provided
- 30 such a device in a form which is simple, efficient and capable of being cheaply manufactured.
- Having thus described my invention, I claim:—
- 35 1. In a device of the character described the combination of a cylindrical container, a hollow conical head mounted at one end thereof, a discharge spout leading from the end of the head, a piston rod having the end
- 40 within the cylinder threaded, a hollow conical piston head having a central boss, said boss having a threaded opening in engagement with the piston rod and the end of said boss being in the same plane with the
- 45 base of the piston head skirt, a pair of oppositely facing packing cups, a washer disposed intermediate the cups, each of said
- 50 cups and said washer having a central opening through which said piston rod extends, the openings in the cup adjacent the piston head being smaller than the diameter of the boss and an abutment on the piston rod beyond the other cup, whereby the piston head acts as a nut having engagement with the adjacent cup in a central region and also in
- 55 an annular region adjacent the flange.
2. In a device of the character described the combination of a cylindrical container, a hollow conical head mounted at one end thereof, a discharge spout leading from the end of the head, a piston rod having the end
- 60 within the cylinder threaded, a hollow piston head having a portion thereof cylindrical in shape and having another portion thereof conical in shape, the cylindrical portion merging with the conical portion, and said piston head having a central boss, said boss having a threaded opening in engagement with the piston rod and the end of said boss being in the same plane with the base, the
- 65 outermost portion of said piston head, the outer surface of the piston head from the base to the apex of the cone being smooth throughout, a pair of oppositely facing packing cups, a washer disposed intermediate the cups, each of said cups and said washer having a central opening through
- 70 which said piston rod extends, the openings in the cup and washer being smaller than the thickness of the boss whereby the cups are supported near the central and peripheral portions by the piston head, a follower in abutting engagement with the innermost packing cup, and a single nut threaded on the piston rod, said nut functioning as an
- 75 abutment for the follower, packing cups and piston as a unit, the cylindrical portion of said piston head being spaced inwardly from one of said packing cups, whereby the material being compressed may urge the packing
- 80 cup against the wall of the container.
- In testimony whereof, I hereunto affix my signature.

WILLIAM L. DEMING.
